US0D1071927S

(12) **United States Design Patent** (10) Patent No.: **US D1,071,927 S**
(45) Date of Patent: ** Apr. 22, 2025

(54) **DETECTION DEVICE DOCK ASSEMBLY**

(71) Applicant: **Calcivis Ltd**, Edinburgh (GB)

(72) Inventors: **Adam Christie**, Edinburgh (GB);
Bruce Vernon, Edinburgh (GB)

(73) Assignee: **Calcivis Limited**, Edinburgh (GB)

(**) Term: **15 Years**

(21) Appl. No.: **29/736,195**

(22) Filed: **May 28, 2020**

(30) **Foreign Application Priority Data**

Nov. 29, 2019 (EM) 007310800-002

(51) **LOC (15) Cl.** **14-02**

(52) **U.S. Cl.**

USPC **D14/356**; D24/111

(57) **CLAIM**

The ornamental design for a detection device dock assembly as shown and described.

DESCRIPTION

FIG. 1 is a top view of the detection device dock assembly;

FIG. 2 is a left side view thereof;

FIG. 3 is a front thereof;

FIG. 4 is a bottom view thereof;

FIG. 5 is a right side view thereof;

FIG. 6 is a back view thereof; and,

FIG. 7 is a top, front, and right side perspective view thereof. The broken line areas in the drawings show portions of the detection device dock assembly that form no part of the claimed design.

1 Claim, 4 Drawing Sheets
